UNITED STATES PATENT OFFICE

MARTIN WOLFMAN, OF BROOKLYN, NEW YORK

DESIGN FOR A DOOR PEEP HOLE FRAME

Application filed June 16, 1932. Serial No. 44,100. Term of patent 3½ years.

To all whom it may concern:

Be it known that I, MARTIN WOLFMAN, a citizen of the United States, and a resident of the borough of Brooklyn, county of Kings, city and State of New York, have invented a new, original, and ornamental Design for a Door Peep Hole Frame, of which the following is a specification, reference being had to the accompanying drawing, forming a part thereof.

Figure 1 of said drawing is a front elevation of a door peep hole frame showing my new design; and

Fig. 2 is a side elevation thereof.

I claim:

The ornamental design for a door peep hole frame as shown.

MARTIN WOLFMAN.
